POSTHOLE DIGGER

Louis L. Navarre, Shreveport, La.

Application October 31, 1949; Serial No. 124,544

3 Claims. (Cl. 294—50.8)

1

This invention relates to new and useful improvements and structural refinements in post hole diggers, and the principal object of the invention is to highly expedite the performance of the hole digging operation by facilitating convenient removal of accumulated mud, soil, et cetera, from the ground engaging tools of the digger.

This object is achieved by the provision of an earth and mud scraper between the tools of the digger, together with means for reciprocating the scraper between the tools in such manner that accumulated earth, mud, et cetera, may be conveniently and expeditiously removed.

Some of the advantages of the invention reside in its simplicity of construction, in its convenient operation as aforesaid, and in its adaptability for use on post hole diggers of different sizes and types.

With the above more important objects and features in view and such other objects and features as may become apparent as this specification proceeds, the invention consists essentially of the arrangement and construction of parts as illustrated in the accompanying drawings, in which:

Figure 1 is an elevational view of a post hole digger having the invention embodied therein;

Figure 2 is another elevational view, taken in the direction of the arrow 2 in Figure 1;

Figure 3 is a cross sectional view, taken substantially in the plane of the line 3—3 in Figure 2;

Figure 4 is a cross sectional detail, taken substantially in the plane of the line 4—4 in Figure 2;

Figure 5 is a fragmentary sectional view on an enlarged scale, this view being taken substantially in the plane of the line 5—5 in Figure 2;

Figure 6 is a perspective view of a latch used in the invention;

Figure 7 is a perspective view of a latch bracket used therein, and

Figure 8 is a perspective view of a stop member used in connection with the bracket illustrated in Figure 7.

Like characters of reference are employed to designate like parts in the specification and throughout the several views.

Referring now to the accompanying drawings in detail, the invention is embodied in a post hole digger designated generally by the reference character 10, this being of a conventional construction and including a pair of substantially upright handles 12, 14 disposed in spaced relation, the lower ends of the handles having secured thereto suitable members 16, 18, respectively.

2

These members, being in the nature of clamps, are mounted upon the lower portions of the handles by a plurality of bolts or screws 20, and it is to be noted that the members 16, 18 are provided integrally with pairs of interfitting ears 22, 24 respectively which are pivotally connected together by a transverse bolt or pin 26, as is best shown in Figure 4.

Suitable ground engaging tools 28 are riveted as at 30 to the members 16, 18, and it is to be observed that by virtue of the pivot 26, the tools 28 may be swung together and apart by the manipulation of the handles 12, 14 in the conventional manner.

15 The essence of novelty in the invention resides in the provision of means for expeditiously removing accumulated earth, mud, et cetera, from the tools 28, these means involving the provision of a vertically elongated guide 32 which is secured adjacent the lower end thereof between the ears 22 of the member 16 and slidably accommodates an upright plunger 34.

To prevent relative rotation thereof, the guide 32 and plunger 34 are preferably polygonal in cross section, and it is to be noted that an earth scraping plate 36, provided with a socket 38, is secured by a transverse pin 40 to the lower end portion of the plunger 34, as is best illustrated in Figure 3.

30 This plate is reciprocable between the tools 28, whereby accumulated mud, soil, et cetera, may be expeditiously scraped from the tools by simply sliding the plunger 34 downwardly in a manner hereinafter to be described. It is to be noted that the plate 36 is of such configuration (see Figure 4) to permit the two tools 28 to be swung toward and away from each other when the handles 12, 14 are manipulated.

35 The sliding of the plunger 34 is effected by means of a foot pedal 42 which is secured to the upper end of the plunger, while a suitable compression spring 44 is positioned on the plunger and on the upper portion of the guide 32, one end of the spring bearing against the foot pedal 42 while the remaining end of the spring bears against the ears 22, whereby the scraping plate 36 is normally urged upwardly, that is, to its inoperative position, as shown in Figure 3. However, by simply stepping upon the foot pedal 42

40 and depressing the same, the plunger 34 together with the plate 36 may be slid downwardly as indicated by the phantom lines in Figure 2, thus effecting the tool scraping operation.

45 Means are provided for locking the plate 36 and the plunger 34 in an upwardly slid position, these means consisting of a latch member 48

which is configurated as is best shown in Figure 6 and includes a pair of spaced ears 50 whereby it may be pivotally mounted by means of a pin 52 at the upper end of the plunger 34 or on the upper portion of the foot pedal 42, as desired. The latch member 48 is formed integrally with a projecting tongue 54 which, in turn, is provided with a cam-surfaced detent unit 56, the latter being separably engageable with a transverse bar member or element 58. This element or member assumes the form of a clamp fabricated integrally from a strap as is best shown in Figure 7, the entire member being secured to the handle 12 by a screw 60 and affording at its free end a substantially flat portion 62 which is adapted to abut a coacting bracket or stop 66 mounted on the handle 14.

The two brackets 58, 66 are adapted to abut each other so as to limit the extent to which the handles 12, 14 may be brought together, but at the same time, the bracket 58 affords a member with which the detent unit 56 may be engaged so as to releasably retain the plunger 34 and the scraper 36 in an upwardly slid position.

It is to be noted that the arrangement of the latch member 48 and of the foot pedal 42 is such that when a foot is applied to the latter, the latch member 48 is automatically depressed so as to disengage the detent unit 56 from the bracket 58, thus facilitating downward sliding of the foot pedal.

Finally, a suitable spring 68 is provided on the pivot 52 in engagement with the tongue 54 of the latch member 48, whereby the detent unit 56 is automatically engaged with the bracket 58 when the plunger 34 is slid upwardly by the action of spring 44.

It is believed that the advantages and use of the invention will be clearly apparent from the foregoing disclosure, and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In a post hole digger, the combination of a pair of spaced juxtaposed and substantially upright handles, pivotally connected members provided at the lower ends of said handles whereby the latter are movable toward and away from each other, coacting ground engaging tools mounted on and depending from said handles, a

stationary guide secured to one of said members, a plunger slidable vertically in said guide, an earth scraping plate mounted on the lower end of said plunger and reciprocable in the space between said tools, a foot pedal provided at the upper end of the plunger for pressing the latter downwardly, resilient means for sliding the plunger upwardly, and means for locking said plunger in its upwardly slid position, wherein said last mentioned means include a laterally projecting element provided on one of said handles, and a spring pressed latch pivotally mounted at the upper end of said plunger, said latch being engageable with said element when the plunger is slid upwardly by said resilient means.

2. A post hole digger comprising a pair of pivotally connected handles, coacting blades on one end portion of said handles, a rod slidable between the handles, a scraping plate on one end of the rod operable between the blades, a split band mounted on one of the handles, a pair of opposed, parallel bars integral with the ends of the split band and projecting therefrom toward the other handle, a resilient bumper integral with the free end of one of said bars and engageable with said other handle, and a latch on the rod engageable with said one bar for releasably securing the scraper in inoperative position.

3. A post hole digger comprising a pair of pivotally connected handles, coacting blades on one end portion of said handles, a scraper comprising a rod slidably mounted between the handles and further comprising a plate on one end of the rod operable between the blades, a foot pedal mounted on the rod, a bar mounted on one of the handles, a spring-loaded latch pivotally mounted on the rod and engageable with the bar for releasably securing the scraper in inoperative position, said latch including an operating handle engageable on the foot lever when said latch is swung to inoperative position, and a coil spring encircling the rod and operatively connected thereto for returning the scraper to inoperative position.
